UNITED STATES PATENT OFFICE.

JAMES SEATH, OF TERRE HAUTE, INDIANA.

CAR-AXLE BOX.

SPECIFICATION forming part of Letters Patent No. 247,695, dated September 27, 1881.

Application filed March 3, 1881. (Model.)

To all whom it may concern:

Be it known that I, JAMES SEATH, of Terre Haute, in the county of Vigo and State of Indiana, have invented a new and useful Improvement in Axle Boxes and Covers, of which the following is a specification.

My invention relates to that class of axle-boxes for car-trucks which have covers sliding in grooves or ways formed on the face of the box; and it has for its object the construction of the box and cover in such manner that the cover cannot be removed while the parts of truck are in working position, and also in such manner that the cover, when closed, will form a tight joint with the face of the box without the use of springs or similar means.

In the accompanying drawings, Figure 1 is a sectional view of my improved axle box and cover, taken on line $x x$ of Fig. 2; and Fig. 2 is a front view of the same.

Similar letters of reference indicate corresponding parts.

A represents the axle-box, and B the cover. The box is formed with its front face, a , slightly inclined toward the body of the truck, and is provided with the projection c at its upper edge and with the side parallel ways or grooves dd . The cover is convex vertically, and formed with lower edge curved under, forming the lip b , and it is provided on its front face with the projection c for lifting the cover.

The top of the box A is provided with pro-

jections, forming the seat a' for the arch-bar or equalizing bar of the truck, and the box is held in place by the pedestal C in the usual manner.

It will be observed that in order to place the cover in the ways or grooves in the box or remove it therefrom the cover has to be brought to nearly a horizontal position to cause the lip b to pass the projection c , and that it must be put in place before the box is secured to the truck, and also that the cover cannot, therefore, be lost or removed while the parts of the truck are in proper position.

It will also be perceived that, owing to the curvature of the cover, a wedging effect is produced between the cover and the edges of the ways or grooves, causing the cover to be held firmly against the face of the box, thus preventing access of dust and all rattling and noise of the cover when the cars are in motion.

Having thus fully described my invention, I claim as new and desire to secure by Letters Patent—

The combination, with an axle-box having the inclined front face, a , projection c at its upper edge, and grooves dd , of a cover, B, having the lip b on its lower end, as shown and described.

JAMES SEATH.
